UNITED STATES PATENT OFFICE.

CONRAD L. SCHWANKE, OF CORNELIUS, OREGON.

ROTARY VALVE FOR INTERNAL-COMBUSTION ENGINES.

1,346,686.

Specification of Letters Patent. Patented July 13, 1920.

Application filed February 3, 1919. Serial No. 274,650.

To all whom it may concern:

Be it known that I, CONRAD L. SCHWANKE, a citizen of the United States, residing at Cornelius, in the county of Washington and State of Oregon, have invented certain new and useful Improvements in Rotary Valves for Internal-Combustion Engines, of which the following is a specification.

The present invention comprehends generally improvements in that class of inventions known as internal combustion engines and more particularly relates to an improved rotary valve therefor.

The invention has for its primary aim and object to provide a device of the above mentioned character designed to be mounted for rotation about the closed upper end of an engine cylinder and provided with a passage way for coacting with the inlet and exhaust ports in the cylinder and the intake and exhaust pipes of the engine for controlling the admission and exhaustion of gases to and from the cylinder.

As an equally important object this invention contemplates the provision of a device of the above mentioned character wherein the valve is of improved construction and is designed with double seating portions for coacting with the corresponding seating portions on the cylinder so that the wearing of the valve will not interfere with its efficiency in operation but on the other hand will tend to increase the effectiveness of the valve when in operation.

The invention also embraces the provision of a device of the above mentioned character wherein improved means is employed and operably connected with the engine shaft and with the valve for rotating the valve in timed relation with the operation of the piston, that is, to cause a complete single revolution of the valve during two complete revolutions of the engine shaft.

It is a more specific object of this invention to provide a device of the above mentioned character wherein improved means is employed for lubricating the valve as it rotates on the seat; and to provide improved resilient means for yieldingly holding the valve on its seat.

Among the other aims and objects of this invention may be recited the provision of a device of the above mentioned character wherein the number of parts are compara-

tively few, the construction simple, the cost 55 of production low and the efficiency high.

Other objects, as well as the nature, characteristic features and scope of this invention will be more readily apparent from the following description taken in connection with the accompanying drawings, and pointed out in the claim, forming a part of this specification.

The invention is clearly illustrated in the accompanying drawings, wherein— 65

Figure 1 is an enlarged fragmentary vertical sectional view showing the valve in position,

Fig. 2 is a horizontal sectional view taken on line 2—2 of Fig. 1, 70

Fig. 3 is a horizontal sectional view taken on line 3—3 of Fig. 1, and

Fig. 4 is a plan detail looking toward the bottom of the valve.

Similar characters of reference are employed in all of the above described views, 75 to indicate corresponding parts.

Referring now, more particularly, to the accompanying drawings, there is provided a jacketed cylinder 1 about the upper portion of which is formed an annular jacketed chamber 2, the jacket of which communicates with the jacket of the cylinder as at 3, the bottom of the chamber being rounded to provide a seating portion 4 for the valve 80 while the opposed upper edges of the jacketed cylinder and the jacketed chamber are formed with annular shoulders 5 which are slightly inclined and constitute the upper seating portion for the valve. The jacketed cylinder and chamber is provided with registering inlet 6 and with registering outlet ports 7, the inlet and outlet ports 6 and 7 respectively communicating with the intake and exhaust pipes 8 and 9 of the engine. 95

Mounted in the top of the jacketed cylinder is a vertically disposed hollow stem 10 while rotatably mounted about the stem and operating in the chamber 2 for controlling the admission and exhaustion of gases to 100 and from the cylinder 1 is the improved valve designated in its entirety by the numeral 11.

In the present instance the valve may be said to be in the form of a cap and consists 105 of a hub 12 rotatably disposed about the stem while projecting from the hub are spokes or arms 13 which are joined with

a rim portion 14, the hub, spokes and rim being relatively flat. Integral with the under surface of the rim medially of the inner and outer edges thereof and depending therefrom is a sleeve body 15 having a port hole 15', the body being disposed in the chamber 2 for rotary movement, the lower edge being rounded as at 16 to coact with the rounded bottom or seating portion 4 in the chamber while the upper portion of the sleeve body 15 is formed on its opposite sides at its point of juncture with the rim with annular ribbed or seating portions 17 which seat upon the seating portions 5 of the chamber. In this connection it is to be understood that the chamber 2 and the sleeve body 15 are so proportioned that the lower rounded edge 16 seats against the seated portion 4 at the time the annular or seating portions 17 seat on the upper seating portions or shoulders 5 of the chamber so that even though wear occurs during the rotation of the valve it will be even and the attachment would tend to increase the effectiveness of the valve when in operation. In other words, this valve is provided with double seating portions making it leakproof while in addition, owing to the peculiar mounting thereof is self-grinding during operation. The outer edge of the rim portion 14 of the valve is formed with a plurality of gear or cog teeth 18 for a purpose which will presently appear.

In order to yieldingly hold the valve in a proper position without interfering with the rotation thereof, the hub portion is formed with a boss 19 which is provided in turn with an annular ball race 20 for receiving ball bearings 21 while arranged about the stem is a washer 22 the under surface of which is provided with a ball race 23 facilitating the retention of the ball bearings. Suitable resilient means such as a relatively light coiled expansion spring 24 is arranged about the stem and has its lower end bearing against the washer 22 and its upper end bearing against another washer 25 disposed about the stem and held in position by the coacting lock nut 26, the latter being adjustable so as to vary the tension of the spring as desired.

In order to lubricate the valve so that in effect it will operate in oil, the upper surface of the jacketed cylinder 1 and the jacketed chamber 2 are provided with integral annular ribs 27 positioned near the shoulders and seatings portion 5 coacting with the chamber 2 in providing an oil reservoir while arranged within the hollow stem are oil conducting pipes 28, said pipes being led from the stem across certain of the spokes as at 29 and have their terminal outlet ends 30 arranged over the inner rib 27 as indicated so as to direct oil down the innermost shoulders and seating portions 5.

For the purpose of operating or rotating

the valve in timed relation with the operation of the piston head 31 in the cylinder 1 a horizontally disposed and rotatably mounted shaft 32 is employed and is designed to be operably connected to a suitable mechanism 70 (not shown) with the engine shaft (not shown) so that rotary motion will be imparted thereto. In addition, this shaft is fitted with a worm gear 33 which meshes with the teeth 18 on the valve so that rotary 75 motion will be imparted to the valve. It is desired that the valve make one complete revolution during two complete revolutions of the engine shaft (not shown) as is customary in motors of the four-cycle type so 80 that as a result the port hole 15' in the sleeve portion of the valve will be properly registered with the registering inlet 6 and intake pipe 8 and with the outlet 7 and the exhaust pipe 9 which registers with the outlet 7 in 85 controlling the admission and exhaustion of gases to and from the cylinder.

It is preferred that a flanged cover 34 be fitted about the stem and engaged with the jacketed chamber so as to protect the valve. 90

The jacketed cylinder of course may be fitted with a spark plug 35 while also arranged in the jacket of the cylinder 1 near the top thereof is a pipe 36 the purpose of which is to insure of the circulation of the 95 water and when the occasion requires to permit the hot water at the top of the cylinder to be drawn off.

It is believed in view of the foregoing description that a further detailed description 10 of the operation of the invention is entirely unnecessary. Likewise, it is believed that the advantages of the invention will be readily apparent. In this connection it should be noted that only a light coiled 10 spring is necessary to hold the valve seated since the force created by the explosion is directed against the sides of the valve or rather those portions of the sides of the valve which close the inlet and outlet ports of the cylinder. 11

Still further embodiments of the invention than those herein especially defined may be resorted to as conditions or preference may dictate, as may be in keeping with the 11 hereto appended claim.

Have thus fully described the invention what is claimed as new and desired to be secured by Letters Patent, is:—

In an engine, a cylinder formed with a 12 closed top, a water jacket entirely about the sides and top of said cylinder, the cylinder being formed with intake and exhaust passages extending through said jacket contiguous to the top of the cylinder, an annular valve casing formed in the jacket concentrically of the cylinder, spaced from the walls of the latter and said jacket, intersected by the passages, and opening through the upper end of the jacket, an annular valve 13

rotatably seated in the valve casing for controlling the passages, and removable therefrom, a gear toothed peripheral edge formed on said valve, a cover fitted over the upper 5 open end of the valve casing, a driven worm gear journaled in said cover and meshing with the gear toothed peripheral edge of the valve, a pivot stem fixed centrally of the

water jacket and having the valve revolvably connected therewith and means carried by 10 the stem and co-acting with the connection for regulating the seating engagement of the valve in the valve casing.

In testimony whereof I affix my signature hereto.

CONRAD L. SCHWANKE.
